UNITED STATES PATENT OFFICE

LOUIS B. RODIN, OF GARY, INDIANA

DESIGN FOR A COIN-OPERATED VENDING MACHINE

Application filed January 30, 1931. Serial No. 38,490. Term of patent 14 years.

To all whom it may concern:

Be it known that I, LOUIS B. RODIN, a citizen of the United States, residing at Gary, in the county of Lake and State of Indiana, have invented a new, original, and ornamental Design for Coin-Operated Vending Machines, of which the following is a specification, reference being made to the accompanying drawing, forming a part thereof, in which—

Fig. 1 is a front elevation, and
Fig. 2 is a side elevation showing my new design.

I claim:
The ornamental design for a coin operated vending machine as shown.

LOUIS B. RODIN.
